OFFICE.

GEORGE C. WRIGHT, OF NEW YORK, N. Y., ASSIGNOR TO E. S. HIGGINS & CO., OF SAME PLACE.

DESIGN FOR A CARPET-PATTERN.

Specification forming part of Design No. 5,606, dated March 5, 1872.

Specification describing a Design for Carpets, invented by GEO. C. WRIGHT, of New York, county of New York, and State of New York.

The nature of my design is fully represented in the accompanying photographic illustration, to which reference is made.

A and B are square figures, alike in construction and ornamentation, alternately scarlet and green. (I do not consider the coloring an essential element of my design.) The horizontal and perpendicular borders of each one are composed of two parallel lines, between which, and at right angles with, are bars and blocks alternately. The borders terminate under a lyre-shaped figure, from which small ornaments radiate toward Fig. C. The figures A and B are connected by cross-bands at D, making two distinct forms of ground-work, E

and F, which are mottled alternately with dark and light shading. Figure E is circular with a leaf or "boss" in center.

I am aware that carpet-designs composed of square figures or panels connected by bands are not new, and do not claim that feature. The distinctive character of my design is found in the figures, bands, mottled grounds, and circles, as combined or "worked up."

What I claim as my invention is—

A design for carpet in which the figures, bands, mottled grounds, and circles are combined substantially in the manner above described.

GEO. C. WRIGHT.
